UNITED STATES PATENT OFFICE.

RUDOLPH ARENDT, OF MAGDEBURG, GERMANY, ASSIGNEE TO H. MUNDLOS & CO., OF MAGDEBURG, GERMANY, A FIRM.

BUTTONHOLE-SEWING MACHINE.

1,083,178.

Specification of Letters Patent. Patented Dec. 30, 1913.

Application filed July 10, 1913. Serial No. 778,252.

To all whom it may concern:

Be it known that I, RUDOLPH ARENDT, a subject of the King of Prussia, residing at Magdeburg, in the Kingdom of Prussia and 5 German Empire, have invented certain new and useful Improvements in and Relating to Buttonhole-Sewing Machines, of which the following is a specification.

My invention relates to button hole sewing machines of the kind in which the side or edge stitches and end or barring stitches are formed alternately in an automatic manner, that is to say, without the necessity of any operation on the part of the operator 10 for changing the mechanism from edge stitches to end stitches and vice versa.

In button hole sewing machines hitherto known mechanisms are employed for automatically changing from the edge to the end 20 stitch formation and vice versa, which are extremely complicated and sensitive and therefore unreliable and owing to their complicated structure only reverse at the predetermined time when an exact coöperation 25 of the several reversing members is insured. In the case of button hole sewing machines of the old kind running at high speeds the required exact coöperation of the parts is not always possible so that it frequently happens 30 that the change from edge to end stitch formation or vice versa does not take place at the proper time, or fails altogether.

The object of my invention is to avoid the complication of the reversing mechanism 35 hitherto used and to employ in place thereof mechanisms which insure a positive reliable and automatic change from edge to end stitch formation and vice versa exactly at the predetermined time even in the case of 40 machines running at high speeds.

In accordance with this invention the cam bar operating the needle bar is acted upon by a cam bar guide formed in the manner of the known stitch adjusting lever, and 45 during the sewing of the button hole this guide by means of a cam plate or the like is at the predetermined times positively and automatically displaced in such a manner that a change from edge to end stitch formation 50 or vice versa takes place.

An embodiment of the invention is diagrammatically illustrated by way of example on the accompanying drawing, wherein—

Figure 1 is a side elevation of the upper

part of the machine with the improved 55 stitch changing means and Fig. 2 a plan of the new device for operating the needle bar.

The button hole sewing machine comprises a work plate *a* and an overhanging arm *b*, the free end of which is formed as usually 60 as a casing for the reception and guidance of the vertical needle bar *d* carrying the needle *c*.

The frame of the needle bar participates together with the needle bar *d* in a lateral 65 displacement transverse to the feed direction of the material the displacement being obtained by means of an angle lever *e* and a reciprocating rod *f*. The displacement of the rod *f* is produced by a cam *g* mounted 70 on the top of a bevel pinion which is driven by another bevel pinion from the main driving shaft *h* of the machine. The needle bar *d* is actuated by the cam rod *f*, which is controlled by a cam bar guide *i* having the 75 shape of a bell-crank lever. This guide *i* is adapted to oscillate about a pivot *k* and is also pivotally connected by the link *l* with the said cam rod *f*. The guide *i* is so arranged that it can be adjusted so as to permit 80 stitches of the desired size and length to be made. According to the thus adjusted position of the cam rod guide, the rod *f* will be given a smaller or larger reciprocating movement and thereby will impart to the 85 needle bar a greater or smaller lateral displacement transversely of the direction of feed of the material.

The shifting of the cam rod guide for the purpose of changing from edge to end stitch 90 formation is effected automatically and positively at the proper moment. In the example here illustrated this is obtained by means of cam projections *m* of the feed plate *n* forming part of the feed mechanism. 95 The nature of the connection of the lever acted upon by the said cam projections with the cam rod guide may vary as desired. In the construction here illustrated a lever *r* rests by means of a roller *o* against the periphery of the feed plate. This lever is rigidly connected with a perpendicular shaft *u*. This shaft *u* carries a lever *s* having a slot which is positively connected by a connecting rod *t* with one arm of the lever *i*. 100 The connecting rod *t* is rendered adjustable in length in any convenient manner. Similarly, the point of connection between the

connecting rod *t* and the slot *s* can be modified by appropriately shifting the pin connecting these parts.

The operation of the novel device for dis-
5 placing the needle bar in a buttonhole sewing
machine is as follows: During the opera-
tion of the machine the needle *c* is given
in a well known manner a vertical recipro-
cating movement and the feed plate *n* an in-
10 termittent or step-wise movement. At the
same time the bevel pinions (which are
driven from the main driving shaft) rotate
the cam *g* by means of which the cam rod *f*
is given a lateral displacement which is con-
15 verted into a short reciprocating movement
by the connection of the cam rod *f* with the
cam rod guide *i*. According to the position
of the cam rod guide *i* which is dependent
20 upon the feed plate *n*, the reciprocating
movement of the cam rod will be larger or
smaller, and the change from edge stitch to
end stitch formation will be automatic and
take place when the roller *s* runs onto the
25 cam curve *m*. The extent of the displace-
ment of the cam rod guide can be regulated
within desired limits, by adjusting the po-

sition of the connecting pin for the rod *t* in
the slot in the part *s*.

What I claim is:

In a buttonhole sewing machine, the com-
bination with a needle bar, of means for
changing the movement of said needle bar
from movement to produce end stitch to
movement to produce edge stitch and vice
versa; said means comprising a cam, a cam
30 rod, a bell-crank lever, a link connecting the
lever and cam rod, a feed plate having cam
projections and arranged to rotate in unison
with said cam, an adjustable rod connected
35 with the bell crank lever, a slotted lever en-
gaging said adjustable rod and adjustable
relative thereto, a second lever connected to
the slotted lever and having an end engag-
ing said feed plate and means connecting
40 the cam rod with said needle bar.
45

In testimony whereof I have affixed my
signature in presence of two witnesses.

RUDOLPH ARENDT.
